UNITED STATES PATENT OFFICE

150,939

DESIGN FOR AN ELECTRIC ORGAN

Paul M. Fuller, Buffalo, N. Y., assignor to The Rudolph Wurlitzer Company, North Tonawanda, N. Y., a corporation of Ohio

Application May 28, 1947, Serial No. 139,333

Term of patent 7 years

(Cl. D56—2)

To all whom it may concern:

Be it known that I, Paul M. Fuller, a citizen of the United States, residing at Buffalo, Erie County, New York, have invented a new, original, and ornamental Design for an Electric Organ, of which the following is a specification, reference being had to the accompanying drawing, forming a part thereof.

Fig. 1 is a perspective view of an electric organ showing my new design, with the keyboard cover in closed position and the music rack retracted; and

Fig. 2 is a front view of the electric organ shown in Fig. 1, with the keyboard cover open and the music rack in extended position.

I claim:

The ornamental design for an electric organ, substantially as shown.

PAUL M. FULLER.
